[73] Assignee: **Motorola, Inc.**, Schaumburg, Ill.

[57] CLAIM

[**] Term: 14 Years

The ornamental design for a combined display and button for portable communication receiver, as shown and described.

[21] Appl. No.: 60,332

DESCRIPTION

[22] Filed: Sep. 26, 1996

FIG. 1 is a front elevational view of a combined display and button for portable communication receiver showing our new design;

[51] LOC (6) Cl. 14-03

FIG. 2 is a bottom plan view thereof;

[52] U.S. Cl. D14/191

FIG. 3 is a top plan view thereof;

[58] Field of Search D14/124, 143,

FIG. 4 is a left side elevational view thereof;

D14/188, 191, 192, 247, 299; D10/46,

FIG. 5 is a right side elevational view thereof; and,

46.1, 94; D21/13, 27, 48; 116/202, 222-225,

FIG. 6 is a front, left side and bottom perspective view

234, 286; 340/311.1; 455/90, 92, 100, 128,

thereof.

344

The broken lines showing a portable communications receiver environment in FIGS. 1-6 are for illustrative purposes only and form no part of the claimed design.
